(57) **CLAIM**

The ornamental design for a docking unit for a mobile waste disposal machine, as shown and described.

DESCRIPTION

FIG. 1 is a perspective view of a docking unit for a mobile waste disposal machine showing our new design.

FIG. 2 is a front elevation view of the docking unit of the instant invention.

FIG. 3 is a rear elevation view of the docking unit of the instant invention.

FIG. 4 is a right side elevation view of the docking unit of the instant invention.

FIG. 5 is a left side elevation view of the docking unit of the instant invention.

FIG. 6 is a top plan view of the docking unit of the instant invention; and,

FIG. 7 is a bottom plan view of the docking unit of the instant invention.
